United States Patent Office

Des. 211,630

Patented July 9, 1968

211,630

FOLDABLE TRAILER

Gordon Hodgson, Longmont, Colo. 80501

Filed May 5, 1967, Ser. No. 6,959

Term of patent 14 years

(CL. D14—3)

FIG. 5

FIG. 1

FIG. 3

FIG. 2

FIGURE 2 is a top view;

The other side view is identical to that of FIGURE 1. I claim:

The ornamental design for a foldable trailer, as shown and described.
